UNITED STATES PATENT OFFICE.

WILLIAM DILLARD LANSDEN, OF NASHVILLE, TENNESSEE.

SAMPLE CASE AND SALES SYSTEM.

Application filed March 10, 1923. Serial No. 624,074.

To all whom it may concern:

Be it known that WILLIAM DILLARD LANSDEN, a citizen of the United States, residing at Nashville, in the county of Davidson and 5 State of Tennessee, has invented certain new and useful Improvements in Sample Cases and Sales Systems, of which the following is a specification.

This invention relates to a novel means 10 for exhibiting samples of goods for sale and providing for the sale of such goods without the use of the usual traveling salesmen.

This invention contemplates and includes a sample case adapted for transportation by 15 mail and provides for the retention and exhibition of a series of addresses and stamps whereby such sample case is directed in transportation from one prospective customer to another to such extent as may be 20 desired, and finally returned to its owner.

Another object is to include within the sample case a card or letter retainer for holding and supplying a plurality of addressed and stamped order blanks.

25 Other objects will be indicated by a careful reading of the following specification and inspection of the attached drawing, the latter forming a part of this specification in which similar characters of reference 30 designate corresponding parts throughout the several views, in which:—

Figure 1 is a top plan view of a sample case showing the cards or envelopes in position in the retainers.

35 Figure 2 is a plan view of the top of the cards used on the outside.

Figure 3 is a view of the back of one of the cards in Figure 2.

40 Figure 4 is a top plan view of one of the order blanks used and carried on the inside retainer, and

Figure 5 is a plan view of the back side of the form shown in Figure 4.

45 To carry out the invention a sample case or receptacle is provided and may be of any suitable size and construction to enable its transportation through the mail and to provide for the reception of such samples of goods and materials as may be for sale.

50 This sample case is indicated by reference character A and card retainers are provided on the outside as at B and on the inside as at C. These card or letter retainers are made the subject matter of a co-pending application and are therefore not herein specifically described.

Generally the outside retainer B includes the side and bottom oppositely flanged sheet metal strips, and the top member, the latter being spaced equi-distant the top ends of 60 the side members. The inwardly projecting flanges engage and retain cards or envelopes arranged there between and the outwardly extending flanges engage the outer face of 65 the top of the sample case and receive the fastening nails or rivets. The inner retainer comprises two parallel flanged walls of similar cross section and purpose as the walls of the outer retainer.

Arranged in the outer card retainers are 70 a series of cards 1 each addressed to a different individual or firm with whom it is desired to do business and the last of the series 2 contains the address of the company or individual to whom the sample case belongs and to whom same will be ultimately delivered as will more clearly hereinafter appear. The upper right hand corner 3 of each of the cards is provided with sufficient postage to carry the case to the next destination in the mails. The reverse or unexposed side of the cards (see Figure 3) contains suitable information or instructions as at 4 to cause the proper proceedings by the various individuals handling same. Carried by 85 the card retainer C within the case are the stamped and addressed order blanks illustrated in Figs. 4 and 5. These blanks may be of any approved type such as will permit the proper carrying out of the present system. In the form shown these blanks comprise a paper body uniformly divided into 90 three main sections 5, 6, and 7 by suitable perforations 8, and the flap portion 9. The upper section 5 has printed on its outside the address of the owner of the case and a suitable stamp to carry same through the mail. The other sections are blank on the outside and on the inside as at 10 there is 95 printed throughout the entire length of the blank suitable matter for an order blank. The inside of the flap 9 is provided with a suitable adhesive material. From the foregoing it will be obvious that the blank can be folded inwardly along the perforations 100 beginning at the lower section 7 and can be closed and sealed by the flap. This operation will expose the address and the stamp in the proper manner.

Presuming now that a company has for 110 the purpose of sale a number of articles and his customers are located, as is quite com-

mon, in numerous cities and States throughout the United States. The company having the goods to sell will place within the sample case suitable exhibits or samples for the inspection of the various customers. Within the case and held in position by the inner retainer C will be a number of stamped and addressed order forms. Or if desired addressed and stamped envelopes containing suitable order blanks may be used. Held by the container without the case will be a series of cards addressed to the various customers and properly stamped with sufficient postage. The last card in this outer container will be addressed to the company owning the sample case. The entire arrangement is then placed in the mails and will be delivered to the customer whose name appears on the first card. This customer will remove the card and note the instructions contained on the back thereof. He will then in accordance with these instructions open the case and write his order on the proper blank furnished and held by the inner retainer and place the same in the mails. The sample case will also be placed in the mail and will proceed to the next customer whose name appears on the card on the outside. This proceeding will continue until the final card is reached which directs the sample case back to the owner.

Obviously the foregoing method of exhibiting goods for sale to distant customers and the placing of orders for such goods will eliminate the necessity of having salesmen on the road, which latter involves such expense as railroad fare, hotel bills, and

general traveling and will permit the sale of goods at comparatively reduced rate. 40

It will also be obvious that various changes in the manner of carrying out this method may be made, it being apparent that various advertising methods may be utilized in conjunction with same. 45

What is claimed as new and useful and desired to be secured by Letters Patent is—

1. A sales system device comprising a sample case adapted to contain samples of goods to be sold, an outer card retainer connected to the case, a plurality of addressed and stamped mailable articles in said retainer containing the addresses of prospective customers, a mailable article in the outer container normally concealed by the first mentioned articles and containing the address of the sender, the back of each one of the first mentioned articles being arranged directly in front of the succeeding articles, so that normally only the address 60 on the outer one of the first mentioned mailing articles is visible. 55

2. A sales system device comprising a case adapted to contain samples of goods to be sold, a container connected to the outer side of said case, a stack of addressed and stamped mailing articles in said container and containing the addresses of prospective customers, the outermost article of the stack normally concealing the addresses on the following articles, and a surface containing the address of the sender and stamps for the return of the case, arranged behind and normally concealed by said articles. 65 70

In testimony whereof I affix my signature.
WILLIAM DILLARD LANSDEN.
